UNITED STATES PATENT OFFICE

2,529,852

DUAL VALVE UNIT

Ward E. Snowden and Harvey F. Raynor, Modesto, Calif., assignors, by mesne assignments, to Ward E. Snowden, Modesto, Calif.

Application April 3, 1945, Serial No. 586,317

1 Claim. (Cl. 277—59)

1

This invention relates in general to fire fighting equipment and in particular the invention is directed to an improved nozzle unit for the discharge of fire fighting substances.

It is an object of the present invention to provide a fire fighting nozzle unit which includes a pair of separate nozzles; said unit being adapted to be connected to separate hoses feeding water and a dry chemical fire extinguishing agent under pressure, and there being manually controlled valves in the unit operative to open the water hose to one nozzle and the dry chemical hose to the other nozzle.

Another object of this invention is to provide a dual nozzle unit, as in the preceding paragraph, in which said valves are arranged for easy one-hand control by the operator, and so that said valves may be opened selectively, or one at a time.

An additional object of the invention is to provide a dual nozzle unit comprising in combination with a body having a pair of separate, parallel passages therethrough from back to front, a valve interposed in each passage, fittings at the rear end of the passages adapted for hose connection, and nozzles at the front end of the passages; each valve including an upstanding control lever, and said levers being arranged for easy one-hand actuation.

A further object of the invention is to produce a simple and inexpensive device and yet one which will be exceedingly effective for the purpose for which it is designed.

These objects are accomplished by means of such structure and relative arrangement of parts as will fully appear by a perusal of the following specification and claim.

In the drawings similar characters of reference indicate corresponding parts in the several views:

Figure 1 is a side elevation of the dual nozzle unit as coupled to a water and a dry chemical hose.

Figure 2 is a sectional elevation of the dual nozzle unit detached from the hoses, and with the nozzles removed.

Figure 3 is a front end view of the dual nozzle unit.

Figure 4 is an enlarged cross section on line 4—4 of Fig. 1.

Figure 5 is a fragmentary view of one of the nozzles, detached.

Referring now more particularly to the characters of reference on the drawings, the numeral 1 indicates the body of the unit, and which body

2

is flat sided and relatively thin from side to side. The body is formed with a pair of vertically spaced passages, indicated at 2 and 3, which extend in substantially parallel relation through the body from the rear to the front thereof.

At the rear end the passages 2 and 3 are provided with fittings 4 and 5 adapted to be connected with hoses 6 and 7 by means of complementary couplings 8 and 9, respectively. The hose 6 carries water under pressure, while the hose 7 carries a dry chemical fire fighting agent in powder form in a stream of high pressure gas, such as nitrogen.

15 At the front end the passages 2 and 3 are formed with enlarged, forwardly opening sockets 10 and 11, each having a gasket 12 in the bottom thereof. A pair of initially separate nozzles 13 and 14 are each formed at the rear end 20 with a cylindrical neck 15 having a stop collar 16 at the front end thereof. The necks 15 removably seat in the corresponding ones of sockets 10 and 11, and abut against the gaskets 12.

Each neck 15 is formed intermediate its ends 25 with a radial pin which engages in a bayonet slot 18 opening into the corresponding one of sockets 10 or 11 from the front of the body, whereby the nozzles 13 and 14 are quick connected with said body. Spring pressed latch fingers 19 pivoted as at 20 in extensions of the locking channels of the bayonet slots 18, normally abut against the pins 17 and prevent removal of the nozzles 13 and 14 from the body. However the latch fingers are accessible, as at 21, for manual depression whereby to clear the pins 17 and permit of easy removal of the nozzles. As the nozzles 13 and 14 are removable, different types of nozzles are usable with the dual valve unit, as for example, fog nozzles, overshot nozzles, etc.

30 35 40 Within the body 1, the passages 3 and 4 are intersected by rotary plug valves indicated at 22 and 23 respectively; such valves running in matching cross bores 24 closed at one end by removable end plates 25 which permit of ready assembly or removal of the valves. The valve passages of valves 22 and 23 are shown at 26.

The valves 22 and 23 are formed with axial stub shafts 27 and 28 respectively which project through opposite sides of the body; the shaft 27 50 having an upstanding radial lever arm 29 thereon, while shaft 28 is fitted with an upstanding radial lever arm 30. The lever arms 29 and 30 project upwardly to upper end terminations substantially equi-distant above the body when said

lever arms are in corresponding on or off positions as hereinafter described. At the upper end thereof each lever arm includes a laterally inwardly projecting finger piece 31.

When the lever arms 29 and 30 are in upwardly and rearwardly inclined position, the valves are closed but when in upwardly and forwardly inclined position, as in Figs. 1 and 2, the valves are open. Movement of the lever arms beyond open or closed positions is limited by suitable stops 32 on the sides of the body 1.

When coupled to hoses 6 and 7, the above described valve unit is operative to discharge water and a dry chemical from nozzles 13 and 14 respectively. By proper manipulation of the lever arms 29 and 30, water or dry chemical alone may be discharged from the corresponding nozzle, or both of these fire fighting agents may be used simultaneously, as conditions may require.

By reason of the proximity of the lever arms 29 and 30, and particularly the finger pieces 31 thereon, the valves can be controlled by one hand.

Additionally, as the body 1 of the nozzle unit is relatively thin from side to side, and as the aforesaid lever arms 29 and 30 are flat in adjacent facing relation to the sides of such body, the nozzle unit can be held in hand and manipulated with greater convenience than otherwise. The arrangement also positions the flat lever arms 29 and 30 edgewise in the direction of manipulation thereof, reducing the likelihood of bending or twisting of said arms.

With respect to the quick connected or detachable nozzles 13 and 14, another advantageous feature of the invention is the fact that the accessible portion 21 of each latch finger 19 is movable or depressible only laterally of the body to permit of quick detachment of the corresponding nozzle. This greatly minimizes accidental release of either of the latch fingers 19 when the nozzle unit is in use, as inadvertent lateral depression of said latch fingers is unlikely as compared to longitudinal motion, for example.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful and upon which Letters Patent is desired.

A dual nozzle unit, for fire fighting, comprising an upstanding, transversely relatively thin body having opposed flat side faces in substantially parallel relation, the body being formed with a pair of longitudinal passages therethrough one above the other, means for connecting inlet and outlet fittings with each of said passages, a valve in each passage, each valve being rotatable about its respective axis, which axis extends transversely of the body in the direction of the thin dimension of said body, an axial stub shaft on each valve, one stub shaft projecting through one flat side face of the body, and the other stub shaft projecting through the opposite flat side face of the body, an upstanding lever arm on each stub shaft, such lever arms being of predetermined differential length, flat and extending upwardly from the stub shafts in close face to face relation with respect to the adjacent side faces of the body, projecting to upper end terminations substantially equi-distant above said body when said lever arms are in predetermined corresponding working positions, and finger pieces on the upper ends of said flat lever arms projecting toward each other for separate or simultaneous engagement by one hand.

WARD E. SNOWDEN.
HARVEY F. RAYNOR.
